TWIN TYPE GEAR PUMP

Fritz Egersdörfer, Berlin, Germany

Application March 4, 1939, Serial No. 259,884
In Germany March 4, 1938

15 Claims.

(Cl. 103—42)

This invention relates to a twin type gear pump which is especially suited for use as a fuel feed pump and for similar purposes where the fuel for internal combustion engines is to be conveyed or shifted.

One of the objects of the improvements is to provide a gear pump in which the chambers enclosing the gear wheels are free of distortion by pipes secured to the pump casing, and in which therefore the chambers enclosing the gear wheels are not deformed and jamming of the gear wheels within the said chambers is avoided. Another object of the improvements is to provide a gear pump which can be manufactured at low cost. With these and other objects in view my invention consists in providing the chambers or bores enclosing the impelling gear wheels in an integral body, and placing the suction and delivery passages in one of the heads of the gear pump, so that the suction and delivery pipes are fixed to the said head. Further, the said suction and delivery passages are connected respectively with suction and delivery chambers communicating with the chambers enclosing the gear wheels through ducts made in the said body, and, preferably, the said ducts and other ducts made in the said body are in the form of bores having circular cross-sections and disposed with their axes parallel to the axes of the chambers enclosing the gear wheels. Therefore, all the said bores can be manufactured on the drilling machine with the body fixed on the table in the same position. Thereby accurate work is insured, and the cost of the manufacture is small.

The character of the invention, however, will be best understood by reference to one of its structural forms as described in the following specification and illustrated in the accompanying drawings in which:

Fig. 1 is a cross sectional view on line 1—1 of Fig. 2, showing a gear pump having the invention applied thereto;

Fig. 2 is an axial section on line 2—2 of Fig. 1;

Fig. 3 is a longitudinal section on line 3—3 of Fig. 1;

Fig. 4 is a longitudinal section on line 4—4 of Fig. 1;

Fig. 5 is a longitudinal section on line 5—5 of Fig. 1;

Fig. 6 is an end view of the cover side of the pump and

Fig. 7 is a cross sectional view on line 7—7 of Fig. 2.

Similar reference numerals denote similar parts in the different views.

Referring now to the drawings in greater detail, the pump casing is formed by a cylindrical body 1 having three parallel axially directed bores 2, 3 and 4 for reception of three intermeshing pinions 5, 6 and 7 forming two pairs of intermeshing fluid-displacing spur gears. Sleeves 8, 9 and 10 form the packing means at the rear faces of the pinions; the sleeves 8 and 10 are in the form of separate members inserted in the casing while the sleeve 9 may be formed by a hub portion or projection of the rear cover 11. On their opposite end faces, the pinions lie liquid tight against a plate 12 interposed between the casing 1 and the front cover 13.

The central pinion 6 is keyed on an operating shaft 14 in a "floating" condition, permitting end-wise relative movement, by a key member 15 or the like, while the pinions 5 and 7 are rotatably mounted on tubular members 60 and 61 fixed within the sleeves 10 and 8, respectively. The operating shaft 14 is supported in the hub portion 9 of the cover 11, with an interposed sleeve or bushing 16 and is resiliently coupled to the motor shaft 18 at 17. A collar 19 on the shaft is sandwiched between packing washers 20, under action of a spring 21. Radial bores 22 in the hollow shaft 14 and in the pinions 5, 6 and 7 admit access of the fluid which is to be moved to all surfaces exposed to friction, thereby ensuring effective lubricating action by said fluid.

Further axially directed bores in the casing form passage channels or ducts for the fluid on the suction and pressure side, and receive control devices and valves, as will be described below; cross channels in the two covers, i. e., outside the casing serve to interconnect the said various bores.

The two suction chambers 23 and 24 of the twin pump communicate with bores 25 and 26 while the pressure chambers 27 and 28 thereof communicate with bores 29 and 30. The bores 25 and 26 communicate with chambers 62 and 63 made in the head 13 and ending in threaded bores 64 and 65 adapted to have suction pipes secured thereto. At their opposite ends and at the side 31 of the casing adjacent to the cover 11 the bores 25 and 26 are normally closed on the side 31 of the casing adjacent to the cover 11, by valves 32 and 33. The valves are guided in the bores, but their springs 34 are disposed in channels 35 made in the cover 11. Thus, in operative condition of the pump, the valves 32, 33 close the suction side against the said channels 35 which through the bores 29 and 30 communicate with the pressure chambers 27 and 28; it is there-

by possible to feed fuel directly to the carburettor of the engine in order to fill up the same prior to the starting of the engine, through the by-pass thus formed as the pressure exerted, for example, by a hand pump, is sufficient to overcome the adjusted compression of the valve springs.

Check valves 36 shut the bores 29 and 30 on the side adjacent to the cover 13 and plate 12 in the inoperative condition of the pump and when the fuel supply is interrupted on either side. The heads of the valves 36 are guided in sleeves 38 which are mounted in the plate 12 and project into the bores 29 and 30 of the casting 1, thus centering the plate 12 and its bores relatively to the body 1 and its bores, while the valves proper with their springs 39 are received in a channel 66 made in the cover 13. A threaded bore 40 (Fig. 4) is provided to permit connection of the channel 66 to a control pressure gauge (not shown). The channel 66 communicates with a central duct 41 in the cover 13 adapted for connection with the pressure pipe to the carburettor. It will be noted that in Figs. 4 and 5 the same bore 30 and its valve 36 and spring 39 have been illustrated. But it will be understood that the bore 29 is provided with a similar valve 36 and spring 39 which are likewise located in the recess 66 communicating with the threaded bore 41, as is shown in Fig. 6.

Seated in two further axially directed bores 43 and 44 in the casing 1, between the bores 25 and 30 or 26 and 29, respectively, are guiding sleeves 45 for control pistons 46. On the side adjacent to the cover 11 the bores 43 and 44 terminate each in one of the channels, 35 communicating with the bores 29, 30 and the pressure chambers 27, 28 of the pairs of gears. By reason of this, the pistons acted upon by pressure springs 47 are adjusted in accordance with the pressure of the fluid within the pressure passages. On the side adjacent to the cover 13 the bores 43, 44 terminate in chambers 48 made in the head 13 which through ducts 68 made in plugs 49 communicate with ducts 69 adapted for connection with the pressure pipe of the compressor of the engine (not shown). In case of engines without supercharging, the chambers 48 communicate directly with the atmosphere. By connecting the chambers 48 with the pressure pipe of the compressor of the engine by two ducts 69 and pipes connected thereto the safety of the system is increased. The plugs 49 are provided with set screws 50 adapted to adjust the tension of the springs 47. At a predetermined pressure within the pressure pipe of the compressor of the engine and within the passages 48 the pistons 46 are lifted by such an amount that a by-pass channel is exposed for establishing communication between the suction and pressure sides. To this end, the bores 43, 44 are formed with annular recesses 51 communicating with bores 25, 26 on the suction side, in the manner indicated in Fig. 1 in dotted lines. Inclined slots 52 provided in the guiding sleeves 45 adjacent to the recesses 51 cause a larger or smaller cross section to be exposed by the pistons depending on their adjustment. Advantageously, the pistons are provided to carry out a rotating motion together with their axial movement and to this end, a pin 54 may project into a helical groove or slot 53 in each of the pistons.

The operation of the pump is as follows: It may be assumed that the pump is used for sup-

plying fuel to an engine provided with a compressor for supplying air under pressure. Before the engine is started fuel is supplied to the suction side of the fuel pump through the bores 64, 65 and the bores 25 and 26 by means of a hand-operated pump. By the pressure built up within the said bores the valves 32 and 33 are unseated, and the fuel flows through the channels 35, the bores 29 and 30, the channel 66 and the bore 41 to the carburettor. Now the engine is started, and the fuel pump connected therewith begins its operation. The fuel is admitted through the bores 64, 65 and 25, 26 to the suction chambers 23, 24, and it is conveyed by the gear wheels 5, 6 and 7 to the bores 29, 30, the channel 66, and the bore 41 to the fuel pipe or pipes connected with the engine. While the fuel thus flows from the bores 29, 30 into the channel 62 it opens the valves 36, 36. The pressure within the said channel may be ascertained by the pressure gauge connected to the bore 40.

The pistons 46 are controlled by the fluid pressure within the channels 35, 35, by the fluid pressure transmitted to the chambers 48 from the pressure pipe of the air compressor of the engine and by the pressure of the springs 47, and they are held in equilibrium and in a position so that there is ordinarily communication through the slots 52 between the bores 25, 26, 30 the channels 35 and the bores 29, 30, so that any excess of fuel supplied by the pump is returned from the channels 35 and through the annular recesses 51 to the bores 25 and 26. Thus constant pressure is maintained at the pressure side of the pump, the said pressure depending on the tension of the springs 47 and the pressure within the channel 48 and the pressure pipe of the air compressor of the engine. If it is desired to supply the air to the engine at higher pressure the tension of the springs 47 must be varied accordingly by means of the screws 50, so that the fuel is still supplied under the desired pressure.

While the engine and the gear pump are out of operation the valves 36 are closed, so that the fuel is not returned from the carburettor to the pump, where it would leak through the spaces between the gear wheels and the walls of their chambers.

It will thus be understood that in my novel gear pump the required smooth slide fit between the axial end faces of the movable parts can be obtained with normal tolerances as there is no summing up of any inaccuracies of the axial dimensions of any parts in a series arrangement. Furthermore, since the pipes are connected to a separate cover, the casing is not stressed by mechanical tensions due to the pipe connections so that the chambers in which the gear wheels are mounted are not deformed and jamming of the gear wheels in the said chambers is avoided. In this respect the construction shown in the drawings in which the plate 12 is interposed between the body 1 and the head 13 is particularly effective, because any stress which might be exerted by the head is taken up by the said plate. This plate also has the result that the passage 66 may be in the form of a channel which is machined in the head by milling, and which in the pump is closed by the head having a close fit on the plate 12. If the plate were not provided it would be necessary to provide a transverse bore in the head in lieu of the channel 66. A further important advantage of my novel gear pump resides in the fact that nearly

all of the surfaces to be machined can be formed by axially directed bores in the casing. Thus, nearly all recesses in the casing, and especially the recesses provided to be in accurately defined mutual relationship can be made with the work piece fixed in the same position on the working table of the machine tool. The machining of the casing is particularly facilitated by the cylindrical shape of the same. Also, as herein shown, the auxiliary devices of the pump, viz, control valves, back pressure valves, by-pass valves and so on can be easily applied in the casing.

I contemplate also that more than three spur gears may be combined according to the principle herein disclosed. For example, four spur gears may be combined in a common casing and in a common plane, thus forming three pairs of fluid-displacing gears and making up together a triple-type pump, or five spur gears may be arranged to form a quadruple-type gear pump, depending on the required output of the pump, as will readily occur to one skilled in the art.

I am aware that many further changes may be made and numerous details of construction may be varied through a wide range without departing from the principles of this invention, and I, therefore, do not purpose limiting the patent granted hereon otherwise than is necessitated by the prior art.

I claim:

1. In a gear pump, comprising a casing having an integral body formed with cylindrical bores disposed one beside the other and with their axes parallel and merging one into the other in pairs, cover means for closing said bores at least at one of their ends, meshing gear wheels within said bores, and driving means for said gear wheels, the improvement which consists in suction and delivery passages formed in the said covering means and constructed for having suction and pressure pipes connected thereto, and suction and delivery chambers and ducts formed in said body, said suction and delivery chambers communicating with said bores and being connected through said ducts respectively with said suction and delivery passages respectively for conveying fluid from said suction passage to said bores and gear wheels and away therefrom to said pressure passage.

2. In a gear pump as claimed in claim 1, the improvement which consists in said ducts connecting the suction and delivery chambers with the suction and delivery passages being in the form of bores of circular cross-section made in the said body and disposed with their axes parallel to the axes of the bores receiving the gear wheels.

3. In a gear pump as claimed in claim 1, the improvement which consists in the said suction and delivery passages being made in the same cover member.

4. In a pump as claimed in claim 1, the improvement which consists in a duct in the pump casing connecting corresponding suction and pressure chambers with each other, and in a valve for normally closing said duct.

5. In a pump as claimed in claim 1, the improvement which consists in a duct in the form of an axial bore of circular cross-section in said body for connecting corresponding suction and pressure chambers with each other, and in a valve for normally closing said duct.

6. In a gear pump as claimed in claim 1, the improvement which consists in a channel in one

of said covering means for connecting a duct connected with a suction chamber with a duct connected with a delivery chamber, and in a spring pressed valve for normally closing said channel made in the covering means, the power of said spring being such that the valve is opened by pressure being built up within the suction chamber connected with said channel.

7. A gear pump, comprising a casing composed of an integral body formed with cylindrical bores disposed one beside the other and with their axes parallel and merging one into the other in pairs, said body having a finished end face, and covering means for said body one located on said finished end face, meshing gear wheels within said bores, driving means for said gear wheels, said covering means being formed with suction and delivery passages, and said body being formed with suction and delivery chambers and bores of circular cross-section located with their axes parallel to the axes of said bores enclosing the gear wheels and connecting said suction and pressure chambers respectively with said suction and delivery passages for conveying fluid from said suction passage to the gear wheels and from the gear wheels to said delivery passage, and said covering means bearing on said finished face being formed with a channel connecting said bores connected respectively with the suction and delivery chambers, and a spring pressed valve for normally closing said channel mounted within the bore connected with said suction passage and seated on said finished end face, the spring acting on said valve having a power such that the valve is unseated by pressure within the bore connected with the suction passage.

8. In a gear pump as claimed in claim 1, the improvement which consists in providing a check valve at the delivery end of the duct connected with the delivery passage for closing the bores containing the gear wheels against the delivery passage.

9. A gear pump, comprising a casing composed of an integral body formed with cylindrical bores disposed one beside the other and with their axes parallel and merging one into the other in pairs, and covering means for said body, one of said covering means comprising a head and a plate located between the said head and one of the end faces of the body, meshing gear wheels within said bores, driving means for said gear wheels, said head being formed with suction and delivery passages, and said body being formed with suction and delivery chambers communicating with said bores, and with bores of circular cross-section located with their axes parallel to the axes of said bores enclosing the gear wheels, said plate being formed with bores in alignment with said bores of circular cross-section, said bores of circular cross-section and bores in said plate connecting said suction and delivery chambers respectively with said suction and delivery passages in said head for conveying fluid from said suction passage to said gear wheels and from said gear wheels to said delivery passage, bushings located in said bores communicating with said delivery chamber and in said bores made in said plate so as to center said plate relatively to said body, and spring pressed check valves guided in and seated on said bushings in position for preventing back-flow of the fluid from said pressure passage through said gear wheels.

10. In a gear pump as claimed in claim 1, the

improvement which consists in a bore made in said body which communicates at one end with said delivery passage and with a suction chamber, said bore being adapted to establish controlled connection between said suction chamber and said pressure passage, and in which a spring controlled piston is disposed within said bore controlling the said controlled connection.

11. In a gear pump as claimed in claim 1, the improvement which consists in a cylindrical bore in said body disposed with its axis parallel to the axes of said bores containing the gear wheels and communicating with said suction chamber, chambers made in opposite covering means one having a supply of a fluid under pressure and the other communicating with said delivery passage, said cylindrical bore parallel to the bores containing the gear wheels being open with its ends to said chambers in the covering means, and a spring pressed piston within said cylindrical bore held in equilibrium therein by the pressure within said delivery passage, the pressure within said chamber having a supply of a fluid under pressure and by said spring and controlling the connection between the said suction chamber and delivery passage.

12. A gear pump, comprising a casing composed of an integral body formed with cylindrical bores disposed one beside the other and with their axes parallel and merging one into the other in pairs, and covering means for said body, meshing gear wheels within said bores, driving means for said gear wheels, said covering means being formed with suction and delivery passages, and said body being formed with suction and delivery chambers communicating with said bores and with said suction and delivery passages for conveying fluid from said suction passage through the gear wheels and to the delivery passage, said body being formed with an axial bore communicating at one end with said delivery passage and having an opening in its wall adapted to establish controlled connection with a suction chamber, a spring pressed piston within the last named bore controlling the said connection, and means for imparting rotary movement to said piston as it moves axially within its bore.

13. In a gear pump as claimed in claim 1, the improvement which consists in a cylindrical bore made in said body and located with its axis parallel to the axes of said bores containing the gear

wheels and open at one end to said pressure passage and having an opening in its wall for establishing connection between a suction chamber and the pressure passage, a piston in said bore adapted to establish connection between said pressure passage and suction chamber, a spring acting on said piston for holding the same in equilibrium with the pressure in said delivery passage, and means for varying the tension of said spring.

14. In a gear pump comprising a casing composed of an integral body and heads secured to the opposite ends thereof, three bores made in said body with their axes parallel and merging one into the other in pairs, meshing impelling gear wheels within said bores, and driving means for said gear wheels, the improvement herein described which consists in suction and delivery passages made in one of said heads, two suction chambers and two pressure chambers made in said body and communicating with said bores at the merging portions thereof, four bores made in said body with their axes parallel to the axes of the said bores enclosing the gear wheels and connected respectively with said suction and pressure chambers and said suction and delivery passages for conveying fluid from the suction side of the pump through said gear wheels and to the pressure side of the pump, channels made in one of said heads in position for connecting in pairs bores connected respectively with said suction and delivery passages, spring pressed valves for normally closing said channels, the power of the springs of said valves being such that the valves are opened by pressure built up at the suction side of the pump, two bores made in said body with their axes parallel to the axes of said gear wheels and open to the pressure side of said pump and having their walls formed with slots adapted to establish communication between the pressure side and the suction side of the pump, and spring pressed pistons within said last named bores controlling said slots.

15. A gear pump as claimed in claim 1, in which a plate is located between the said body and the cover means having said suction and delivery passages formed therein, and in which one of the said passages is in the form of an open channel made in the said cover means and closed by the said plate.

FRITZ EGERSDÖRFER.
